UNITED STATES PATENT OFFICE.

HENRY JAMES HERINK, OF LONDON, ENGLAND, ASSIGNOR TO THE RELAY AUTOMATIC TELEPHONE COMPANY, LIMITED, OF LONDON, ENGLAND.

TELEPHONE SYSTEM.

1,424,644

Specification of Letters Patent. Patented Aug. 1, 1922.

Application filed November 10, 1916. Serial No. 130,551.

To all whom it may concern:

Be it known that I, HENRY JAMES HERINK, a subject of the King of Great Britain, residing at Marconi House, Strand, London, England, have invented new and useful Improvements in Telephone Systems, of which the following is a specification.

The invention relates to automatic and semi-automatic telephone systems, and more particularly to systems of the kind in which the subscribers of an automatic exchange are able to establish connections over automatic switches, both with other subscribers and with an operator for enquiry purposes or for the extension of the connection to a trunk or other line. Among the enquiry purposes may be included calls which will become connected to an operator or operator's position owing to a calling subscriber calling in a group in which no subscribers' lines are connected or calling a subscriber's number from which the line has been purposely disconnected or the like.

The object of the invention is so to arrange the circuits that the same connecting apparatus and junction lines may be used both for connection between two subscribers and between a subscriber and an operator, with the difference, however, that when an operator is called, current feeding bridge controlling relays and condensers associated with a junction line are automatically disconnected from the line, the subscriber being supplied with current from the operator's cord circuit, and the control of the circuit being transferred to the operator.

Another object of the invention is so to arrange the circuits that other operations such as metering, disconnecting and controlling supervisory signals and discriminating tones, may be performed according to the class of connection established.

The invention also relates to calls to be completed by an operator with the object of setting up a connection with any subscriber connected to the automatic or semi-automatic system.

In a system according to this invention, a calling subscriber is normally supplied with current from the junction line leading to the first digit selecting stage, while the called subscriber receives current either

from the same stage or from the final connecting stage, the subscriber's metering being carried out in any known manner. 55

According to the present invention, the junctions have associated with them discriminating means, which, upon a connection being established with a manual switchboard, are operated so as to clear the line 60 from certain apparatus connected thereto and to cause circuit changes whereby the control of the connection, including release and metering, is transferred to the operator. The manual board may be located at the 65 same or at a distant exchange.

The discriminating means are also operated in a manner dependent upon the successful completion of a call to another subscriber, in order to cause metering, either 70 immediately the required subscriber lifts the receiver, or at the conclusion of conversation, before, concurrently with, or after release of the connecting junctions. The junctions from the manual switchboard terminate at the automatic first digit switching stage, and means are provided for enabling the operator to obtain access to any subscriber and to establish a clear connection between the operator's cord circuit with 80 bridges, condensers and other apparatus removed from the junction circuit. 75

The discriminating means may be a relay, or relay arrangement capable of being operated over the connection at different 85 stages.

Further features of the invention will be described in connection with the accompanying drawings in which Figure 1 shows that part of a talking connection which is 90 associated with the subscriber's line and the junction to the pre-digit stage with the principal circuits of a set of relay combinations according to part of the invention.

Figure 2 shows that part of a talking 95 connection which is associated with the final or connector end of the circuit.

Figure 2^a shows the modification necessary in Figure 2 if the operator is required to meter a call completed by her. 100

Figure 3 shows that part of a talking circuit (together with its associated relays) which is connected either to Figure 1 or Figure 2, when a call is made to an operator.

- This part of the circuit may be directly connected as a junction leading from any of the digit stages, in which case it will be connected directly to Figure 1 when talking, 5 or it may be connected in the place of a subscriber's line, in which case it will when talking be connected to the calling subscriber's line over Figures 1 and 2 connected together.
- 10 Figure 4 shows that part of the talking circuit which is associated with the called subscriber's line, and is, when talking, attached to Figure 2.
- Figure 5 shows a cord circuit, which, 15 when a call is answered by an operator, is connected to Figure 3.
- Figure 6 shows another arrangement but similar in its operation to Figure 1.
- Figure 7 is similar to Figure 2 but is designed to co-operate with Figure 6.
- 20 Figure 8 is similar to Figure 3 but is designed to co-operate with Figures 6 and 7. It is also designed to be connected to the termination of a junction from a digit stage.
- 25 It is obvious to anyone skilled in the art that with little modification this part of the invention might be connected to the ordinary subscriber's line equipment as in the case of Figure 3.
- 30 The cord circuit to be used with Figure 8 is one similar to that shown in Figure 5.
- Figure 9 is another illustration of the invention and is used similarly to Figures 1 and 6. Two relays are shown each attached 35 to one line branch of the talking circuit to effect the circuit changes according to the class of connection established. These relays are used to feed the called subscriber with talking current on such a connection.
- 40 Figure 10 resembles Figures 2 and 7 but is adapted to co-operate with Figure 9.
- Figure 11 resembles Figures 4 and 8 but is used with Figures 9 and 10.
- 45 Figure 12 illustrates a circuit to which are connected those lines purposely disconnected from the ordinary equipment. When a subscriber calls for one of these lines, the line calling is connected to the circuit shown over Figures 1 and 2, Figures 6 and 7, or 50 Figures 9 and 10.
- 55 Figures 13 and 14 illustrate the circuit for the junctions connected from the manual switchboard to the first digit switching stage, so that an operator may obtain access to any of the automatic subscribers.
- 60 Figures 3, 8 and 11 may be connected to levels at any stage in which there are no further junctions or subscribers' lines, so that subscribers calling into these levels are connected to the circuit in a known manner, the release and the like being controlled as hereinafter described.
- 65 In Figure 1, LR and COR are the line and cut off relays respectively usually particular to each subscriber's line. IR is an impulse relay associated with the junction pertaining to the pre-digit stage and when energized it causes a guarding relay GR to energize so that it may prevent the circuit from releasing during the transmission of 70 impulses. The latter relay has during this period, a secondary winding which is short-circuited, thus rendering the relay slow. 1CR is a slow relay which energizes during each train of impulses and opens the transmission circuit during these periods.
- 75 MR is a relay used for metering.
- SR is the current feeding relay which supplies talking current to the calling subscriber.
- 80 This relay cannot be switched into circuit until the required subscriber has answered. By using a different relay as the impulse relay it is possible to employ a wider range of sensibility of the latter relay than 85 when the relays are one and the same.
- S1R is the current feeding relay for the called subscriber or station, and is not normally in a circuit until the called subscriber replies. DR is a differentially wound relay 90 through which the impulses are transmitted. It is normally attached to one line branch of the talking circuit except during the transmission of impulses, when it is attached to both line branches. It is slow to release and 95 is so connected that it is thrown on a maintaining circuit dependent upon the loop from the called end.
- This relay is also responsible for metering a successful call to a subscriber, its 100 operations being fully described later. Resistance R is in the metering circuit, and the increase of current due to its being shortcircuited causes the subscriber's meter to operate.
- 105 BSR is a relay which, on being prematurely de-energized, causes a relay BR to energize thus giving busy tone to the calling subscriber from BB. BSR when energized also maintains the guarding circuit 110 so that GR cannot de-energize when the circuit is extended to an operator's position.
- TCR is a switching relay, slow to operate and is used to switch out and in other relays in a manner hereinafter explained.
- 115 In Figure 2 CR3 and CR4 are connecting relays. FCR is a relay energized from a selecting device not forming part of this invention.
- 120 FTR is a relay energized to switch in the ringing circuit and RCR is a relay which is energized when the called subscriber replies and under similar conditions, and which maintains itself in the circuit formed by its second winding. Its operation cuts out FTR 125 the time interval between these operations being utilized to send a momentary current over the junction.
- 130 In Figure 2^a MMR is a marginal relay energized when the current is increased by

exterior means. This relay, when energized, shortcircuits resistance R2 thus increasing the current.

In the case of a call to a subscriber, figure 5 2 would be connected directly to Figure 4. The resistance of RCR in Figure 2 is such that SM2 in Figure 4 will not be energized.

In Figure 3 L1R is the calling relay operated from the calling subscriber's loop. 10 CO1R is a cut off relay energized by the insertion of the operator's plug shown in Figure 5. MRR is a metering relay energized when the operator depresses the metering key MK in Figure 5. RR is a slow release relay which controls the release of the 15 circuit. The time taken for it to fall off is sufficient to allow the relays maintaining the connection to clear.

In Figure 6 the relay combinations are 20 different from those of Figure 1 but the operations of the circuit are similar. TKR is a slow release relay which is attached to one line branch and shortcircuited during the transmission of impulses. It is operated by a signal sent over this line branch when the called subscriber answers or when the circuit is connected to an operator's line. TKR energizes MKR which in turn energizes TSR which switches out TKR. During 25 the time TKR takes to fall off, MKR depends for its maintenance on S1R, which may or may not become energized and thus depends upon the establishment of a loop in the succeeding stages.

If a loop be not established MKR de-energizes before TKR and cannot further be energized.

This will result in the establishment of a clear line circuit in the connection. Thus 40 it will readily be seen, that if TKR is energized before the establishment of a loop, a clear line circuit is established. This is accomplished by an operator's circuit Figure 2. The circuit is for the sake of brevity 45 shown only connected to a special level assigned. It is clear that it may be modified to be connected to the final stage as in Figure 3.

In Figure 9 the operation of the circuit 50 depends upon the energization of said relays S1R, S2R, in a specific order. If S2R be energized before S1R a clear circuit is established, removing feeding bridges, condensers and the like.

In an ordinary connection S1R is energized during the ringing period and S2R when the called subscriber answers. MR will in this case energize and bring about registration. The other relays are similar 60 in action to those described for Figure 1 except that if BSR ever falls off the connection is totally released back to the calling subscriber who receives busy tone in a known manner.

65 The functions of the apparatus shown in

Figures 1, 2 and 4 will now be described in connection with the operation of the circuits which is as follows:—

Circuit 0. When the receiver is lifted, LR is energized. 70

The method of connecting with an idle trunk forms no part of this invention and may be performed in any known electro-mechanical stepping or relay system. CR1 and CR2 connect in the manner described in 75 Patent No. 1,234,610, Betulander and Palmgren, July 24, 1917.

Circuit 1. IR energizes over the extended caller's line.

Circuit 2. GR is energized over one winding.

Circuit 3. BSR energizes over a common impulse selector at the first digit stage (not shown but described in Patent No. 1162556 85 Betulander and Palmgren, Nov. 30, 1915.

Circuit 4. COR energizes in circuit 4 completed by GR. SM is biased against this current. CR1 and CR2 are held energized in this circuit.

Circuit 4'. GR shortcircuited to make it 90 slow to release. The caller now sends in the impulses of the first digit in a known manner. When 1 is opened for the first impulse, IR de-energizes. GR being slow to release maintains the connection. 95

Circuit 5. ICR energizes and remains energized for the duration of a train of impulses. It opens the circuit to the condensers so that they do not interfere with the efficiency of the impulses repeated.

Circuit 6. IR by back contacts 6 completes a circuit over the trunk to the first digit stage through both windings of the differentially wound relay DR (which is also slow to release). DR does not energize. IR energizes at the termination of the impulse. The impulse has thus been repeated to the first digit stage. At the end of a train of impulses ICR de-energizes and restores the transmission circuit. The impulses affect 110 circuit changes in a known manner to energize connecting apparatus, such as CR3 and CR4, to extend the circuit to another switching stage. 100

Figure 2 shows the connection extended to 115 a final switching stage in which CR3 and CR4 have been energized and are retained in an extension of 3, marked 3^b, the circuit being completed over the common impulse selector apparatus (not shown). BSR thus 120 remains energized.

The selector, represented by relays CR3 and CR4, makes connection between trunks, as described in the specifications of Patents Nos. 1162556 and 1195771 Betulander and 125 Palmgren, Aug. 22, 1916.

The caller now sends in the two final trains of impulses to select the tens and units; IR, GR and ICR operate as before described, and the impulses are repeated over 130

6. At the termination of each train of impulses ICR de-energizes. The impulse selector having responded, CR7 and CR8 (Figure 4) are energized and FCR (Figure 5 2) is also energized over 7.

Circuit 8. A retaining circuit is then completed in which CO2R and FTR are energized and CR5 and CR6 retained. Circuit 3^b for BSR is completed over FTR and FCR, 10 the latter having a retaining winding in this circuit. CO2R cuts off the called party's line relay L2R. SM2 is biased against this current.

Circuit 9. The ringing circuit to call the party wanted is completed through a winding of RCR. When the called party lifts his receiver, RCR energizes and locks up over 8^b. 8 being opened, FTR de-energizes. BSR is maintained energized by an extension of 3^b over RCR.

Circuit 10. Between the energizing of RCR and the de-energizing of FTR, 10 is completed over one wire of the trunk to energize DR which retains over 10^a.

Circuit 11. S1R is connected to trunk and maintained energized over the called party's line.

Circuit 12. SR is energized by S1R and connected to the caller's line over contacts 30 12^a of SR.

Circuit 13. TCR is first energized over a contact of DR.

Circuit 13^a. TCR retaining circuit. TCR opens circuit 10^a of DR but an alternative circuit 10^b for DR is completed by S1R.

Circuit 14. MR is energized over 14 and retained over 14^a. IR de-energizes. GR is retained over 2^a, 2^b and 2^d. It can only 40 be de-energized by a current in the second winding. BSR circuit 3 is now extended by TCR over 3^a.

Circuit 12^b. Subscribers S1 and S2 are now connected for talking. The power to 45 disconnect the circuit is in the control of station S1. If S2 replaces his receiver, S1R de-energizes, but DR is maintained over 10^c. If S1 replaces his receiver 12^a is opened and SR de-energizes. 4^b is then 50 completed to shunt resistance R by second winding of GR. The increased current in meter SM causes it to register. SM short-circuits COR and thereby increases the current in 4^b to de-energize GR.

GR de-energizing opens 3^b, 4 and 3^a, causing all relays maintained thereby to de-energize, to restore the circuit to normal.

If the called party had been engaged, connecting relays CR7, CR8 (Figure 4) would 60 not be energized and 3^b would not therefore be completed. The final common impulse selector releasing would open 3, BSR would de-energize, BR energize over 3^c to complete 3^d to give busy tone to the caller. 65 10 would not be completed to energize DR

and therefore S1R, SR, TCR and MR would not energize, so that the attempted call would not be registered. The caller S1 replacing his receiver opens 1 to de-energize IR. IR opens 2 to de-energize GR which opens 4 70 to de-energize CR1, CR2 and COR to release the connection.

When a call is effective, it may be necessary to release it for a trunk or other special call and the circuit lends itself to such possible clearing although this is not shown. For example, if 4 be opened, CR1 and CR2 75 will de-energize, causing IR and GR to de-energize in turn, so releasing the connection without metering.

Connection to an operator's position is shown in Figures 1, 2^a, 3 and 5, circuits 1 to 7 being completed as before described. FTR energizes over 8^a, Figures 2^a and 3, and 9^a is completed so that RCR immediately 85 energizes in series with one winding L1R. DR is energized in 10^a, as before described. TCR energizes over 13. S1R cannot energize, however, because it is connected in 11^a with opposing voltage. DR is thereby de-energized and re-energizes ICR over 5^a. TCR maintains itself over 13^a and causes IR to de-energize. GR is now maintained over 2^a, and consequently dependent upon BSR. MR being a marginal relay will not 95 energize in circuit 3^a. The calling line is thus extended to L1R, Figure 3, over 12^a. L1R energizing renders the circuit inaccessible to other calls in a known manner and glows lamp CL over 15. BR (slow 100 to release) is energized over 8^c, 8^d.

Should the caller replace his receiver before the operator answers, L1R will de-energize and open 15 and circuit 8^d. RR de-energizes slowly so that RCR de-energizing 105 rapidly opens 3^b to de-energize CR3, CR4, and BSR. The circuit is broken down as before described without metering.

If the call is sustained, the insertion of the plug P, Figure 5, to answer completes a circuit 16 in which CO1R is energized in series with the shunted lamp CL1. L1R de-energizes and CL ceases to glow. L1R and RR transfer 8^d to 8^c and RR is retained over 17. P must now be withdrawn to de-energize 110 CO1R before RCR can de-energize, thus the release of the connection is now controlled by the operator.

The operator answers the call in any known manner. The caller by moving the 120 switch-hook can open 12^c without releasing the connection and flash lamp CL1 in a known manner.

The operator completes the connection required in a known manner and will meter or 125 refrain from metering as required. The withdrawal of the plug or the depression of the meter key will release the connection.

In the case of non-metering, the withdrawal of the plug de-energizes CO1R to 130

open 8°. RCR de-energizes and opens 3°. The relays maintained in this circuit all de-energize and GR therefore clears down the connection as previously described. RR is 5 slow to deenergize.

In the case of the operator metering, she depresses key MK (Figure 5) and causes MRR to energize over 16°. MRR switches in 16° and causes the operator's meter OSM to 10 register in a well known manner. Resistance R3 is now shortcircuited by 8d, and MMR energizes. This relay shortcircuits resistance R² by 3° and causes MR to energize. This switches the second winding of GR 15 through 4°, thus causing the calling subscriber's meter SM to energize as before. The current being increased in the second winding of GR causes it to fall off, clearing down the whole connection in the manner 20 previously described. The operator then removes the plug. CO1R when energized makes the circuit inaccessible to any further connections in a manner which does not form part of this invention.

25 In the case of the operator's lines being connected to a special level at an intermediate switching stage, the calling subscriber will only send in the requisite number of trains of impulses. In such a case 30 Figure 1 will be connected directly to Figure 3 over the first (or second, as the case may be) digit switching stage. The impulse selector pertaining to said stage will energize CR5 and CR6 as before, and will switch 35 3 through to 3d.

DR will energize from the earth on L1R as before. S1R and SR will not become energized and consequently DR will de-energize. 1CR energizes by 1R de-energizing 40 after TCR energizes. It can readily be seen that subsequent operations are exactly as those described for an operator's connection.

From this it is apparent that Figure 3 represents a circuit that may be connected to 45 any level at any digit switching stage which has no subsequent stage equipped, so that a calling subscriber calling into said level will connect with an operator's position.

In the case of subscribers calling dead 50 numbers, the latter lines are connected to Figure 12. Figure 12 is a dead number circuit. The portions marked X are removed from the subscriber's equipment and the dotted portion added when a line becomes 55 dead. Any number up to one hundred lines may be connected to one circuit. A subscriber calling any one of these numbers is connected over Figures 1 and 2 to the first line equipment of that number and FTR of 60 Figure 2 is extended over 8° of Figure 12 and energizes cut off relay CO3R. FTR and CO3R energizes the latter making the circuit busy in a known manner. FTR applies ringing current over 12° of Figure 12 but 65 RCR immediately energizes over 9° as de-

scribed for an operator's connection. Now DR of Figure 1 cannot remain energized because S1R of Figure 1 cannot energize and, as before, the calling subscriber's loop is switched through direct, without any current feeding bridges to relay LCR. This relay energizes and closes 18 causing lamp CLX to glow. Also LCR by extending 8° to 8° energizes ARR switching in maintaining circuit 19 for relay CO3R.

70 The operator actuates key LK and informs the calling subscriber that the number for which he called has ceased to be a subscriber. LK disconnects 18 and extinguishes CLX. The subscriber maintains the control of the 80 circuit by keeping LCR energized and he may clear at any time. The replacement of his receiver will cause LCR to de-energize, thus opening 8° and causing ARR to de-energize but too late to prevent RCR of Figure 2 de-energizing before 8° is restored. RCR will release the whole connection as 85 previously described.

When LCR de-energizes circuit 18° is completed and interrupter I flashes lamp C4 90 informing the operator of the clearance, and she will immediately restore LK to normal.

The arrangements are not limited to those described as it is clear that the control of the circuit may be passed to the operator by 95 the addition of relays such as described for Figure 3.

A local connection will now be described in connection with Figures 6 and 7. The called subscriber's circuit is similar to Figure 4 and need not be specially described again.

When the calling subscriber lifts his receiver his line is connected, as described for Figure 1 to trunk T1 at the first group 105 switching stage. Circuit 1 operates 1R and completing 2 causes BSR to energize over the common impulse selector as before described.

GR now energizes over 3, its second winding being shortcircuited over 3°. This relay is now rendered independent of BSR owing to its contact A5 now forming part of 3 and BSR maintains itself over 2° and is therefore independent of 1R. COR, but not 115 SM, now energizes over 4. 1CR during impulsion is energized over 5, and removes the condensers from the circuit, whilst the impulses are repeated to the first group selector over 6. TKR is attached to one line 120 branch of the repeating circuit, but is shortcircuited by the selector having an earth connection on the same line branch. TKR is therefore rendered inoperative and can in no way interfere with the impulses. The 125 first group selector connects up T1 to T2 as in the case of Figures 1 and 2. The second and third trains of impulses operate as before and this final group selector energizes FCR over 7, and connects circuit of Figure 130

7 to the called subscriber as before described. BSR is now maintained over 2^a, FTR and the cut off relay having become energized over 8 through the connecting relays, as described for Figures 1 and 2. FTR switches on the ringing current for the called subscriber's line, and when he removes his receiver RCR energizes through the loop over 9.

10 RCR cuts out FTR as described for Figure 2, but during the time the latter relay takes to de-energize, a current is sent over one line branch, and energizes TKR over 10, this relay holding itself over 11. TKR also 15 switches in S1R which energizes over the called subscriber's loop 12. MKR is energized over 13, and then TSR energizes over 14, and holds itself over 14^a. The latter relay opens 11 and 13 and TKR de-energizes. Supposing S1R to be also de-energized, MKR would de-energize first. TKR being a slow releasing relay, but if S1R be energized during the time TKR takes to de-energize, then MKR will be maintained over 20 13^a, and thus rendered independent of S1R.

This combination is really a testing and metering device, the meter relay being MKR which is for a short space of time thrown on to S1R in order to test whether the called 30 subscriber has answered. The said subscriber may replace his receiver at any subsequent time but metering will now take place independently of any action he may take.

35 TSR opens the shortcircuited winding of GR.

The calling subscriber S1 is now able to speak to the called subscriber S2 over 15. Should S2 replace his receiver S1R will de-energize with no further result.

40 Upon S1 replacing his receiver, 1 is opened, 1R de-energizes and the second winding of GR is now switched over 4^a whilst the first winding is energized over 3^b. Calling subscriber's meter SM energizes, 45 shortcircuiting COR and increasing the current in the second winding of GR causes it to de-energize, thus releasing the entire connection.

During the time S1 and S2 were conversing, if by some external means the 50 retaining circuit 4 were opened, CR1 and CR2 de-energizing would cause 1R to de-energize, and thus release GR destroying the connection without causing SM to energize. Similarly, if 2^a be opened, BSR will 55 de-energize causing 15^a to be established thus giving busy tone to S1 and releasing the trunk leading from the first switching stage. The caller will clear, causing 1R to de-energize, thus de-energizing GR by opening 3 which will release the connection.

If 8^a were opened, RCR would de-energize, and opening 2^a would de-energize BSR to give busy tone to S1, who would replace receiver and cause release without metering 65 as described before. Therefore it is clear

that the trunks, with the exception of that leading to the first digit stage will be released by the interruption of the retaining circuit by a trunk operator, or by any other external means. The calling subscriber replacing his receiver releases the remainder of the connection without causing registration on the calling subscriber's meter. This feature is an important part of the invention. Should the called subscriber be engaged with another line when called by S1, CR3 and CR4 would in the manner explained for Figure 1 not have become energized and therefore 2^a would not have been established. BSR would de-energize releasing the outward trunk and establishing 15^a give busy tone to S1.

TKR, TSR, MKR and S1R do not in this case become energized and 4^a is therefore not established. The replacement of 85 the calling subscriber's receiver, opening 1 causes 1R to de-energize, and 3 being opened GR de-energizes, and opening 4 releases the connection entirely. Thus in Figures 6 and 7 as in Figures 1 and 2 the calling subscriber controls the release of the trunk leading to the first group switching stage on calls made to engage lines, and controls the release of the whole connection, unless the said connection be interrupted by a 90 more favoured connection or by any other means, when, if the interruption be beyond the first group switching stage, the connection is released beyond that stage, and if the interruption be before the first group 100 switching stage the connection is entirely released, metering in no case taking place.

A connection to an operator's line shown in Figure 8 will now be described in connection with Figure 6. It is assumed that 105 the said line is connected to the first group switching stage, though it is obvious to anyone skilled in the art that such a circuit could be connected at any stage as in the case of Figure 3. The first stage of the connection has already been described and need not be repeated.

The selectors concerned set up the connection, and trunk T1 is joined through to T3. CR5 and CR6 being energized, BSR 115 is maintained over 2^a, (Figures 6 and 8) negative from one line branch over L2R energizes TKR over 10^a. MKR and TSR energize as before; TSR will remain energized, but MKR and TKR will deenergize, 120 the former because S1R does not become energized. A clear line circuit is therefore established from S1 to L2R over 15^a, GR being maintained over 3^b and dependent upon the maintenance of the energization 125 of BSR. L2R energizes and completes 18, causing CL3 to glow, and extends 2^a to 2^b thus energizing RR which is slow to release. Now S1 may clear before the operator answers by causing L2R to de-energize and 130

opening 2^a, thus releasing BSR before RR de-energizes. BSR releasing causes GR to de-energize, thus opening 4 and entirely releasing the connection without causing metering.

Should the operator answer by inserting a plug 16 energizes CO1R and RR maintains itself over 17, L2R de-energizes and extinguishes CL3 while 2^a is extended to 2^b. 10 S1 is now able to talk to the operator over 12^a. Should the operator desire to meter, she will cause MRR to energize as before over 16^a, thus extending 2^a to 2^b and short-circuiting R1 and causing MR (Figure 6) 15 to energize, thus extending 4 to 4^a, and so shortcircuiting resistance R. This causes SM to energize, registering the call but does not cause GR to de-energize, and thus the circuit is not cleared down. This is accomplished by the withdrawal of the operator's 20 plug, opening 16, when CO1R falls off thus opening 2^a and 2^b. 17 is also opened but BSR de-energizes before RR. GR having 25 3^a opened, de-energizes and releases the circuit in the manner previously described. In this case it is seen that metering from the operator does not release the connection, but it is clear that with a slight modification this could be accomplished as in the case 30 of Figures 1 and 3.

A local connection will now be described in connection with Figures 9 and 10, and a call to an operator in connection with Figures 9 and 11. For the sake of clearness 35 the operator's line is taken as being connected to the first group-switching stage, but it is obvious that it may form part of any stage, as in the case of Figure 3.

In Figure 9, the calling subscriber S1 is 40 connected to three relays and a meter particular to his line. LR is the line relay, COR the cut off relay and AR a slow release relay. These relays operate in a manner which forms no part of this invention 45 being described in Serial No. 101769. SM is the subscriber's meter to register only effective calls in the manner to be described.

S1 on lifting his receiver completes 1 and energizes LR which, as previously explained, 50 causes said subscriber's line to be connected to a first group switching trunk T1. 2 being completed, energizes IR; BSR and GR energize over 3 and 4 respectively, and as previously described BSR becomes dependent 55 on GR. These two relays complete 5 and COR energizes cutting out 1 and LR.

AR energizes over 6. It is obvious that if BSR or GR de-energizes, 5 will be opened and COR, CR1 and CR2 will de-energize. 60 AR will now be energized over 6^a through loop of S1, and busy tone from BB will be given to S1, the connection being entirely released. During the impulsive periods, ICR energizes over 7 and the impulses are 65 repeated over 8, S1R and S2R and the con-

densers being removed from the circuit by ICR during these periods. T1 is eventually joined to T2 in the same manner as for Figures 1 and 2. In Figure 10 FCR is energized by the final selector over 9 and FTR 70 energized over called subscriber's cut off relay over 10. S1R energizes over 13 (the negative of S1R being of higher potential than that on contact of FTR; the object of this is that if the ringing be of long duration, S1R will not be heated). This is brought about for reasons that will become apparent.

FTR also rings the required subscriber over 12, and when he removes his receiver 80 RCR energizes over 12 and retains over 10^a, cutting out FTR which de-energizes. S2R now energizes over 13 thus energizing MR over 14 which maintains itself over 14^a, MR opening the shortcircuited winding of GR. 85 S1 is now able to talk to the called subscriber over 12^a, S1 receiving talking current from 1R and the called subscriber over S1R and S2R.

If the latter replace his receiver, these 90 relays de-energize but nothing further happens. When S1 replaces his receiver, 2 being opened causes IR to de-energize. This extends 5 to 5^b, shortcircuiting R and causing subscriber's meter SM to energize, thus 95 shortcircuiting COR and increasing the current in the second winding of GR which causes it to de-energize, thus completely releasing the connection by opening all retaining circuits.

Should the required subscriber be engaged at the time of calling, BSR would be de-energized as previously described. 5 being open would release the entire connection and busy tone would be given over 6^a as 105 already explained. Metering cannot take place, because 5^b is never switched in. If the called subscriber does not answer and S1 replace his receiver, IR de-energizing causes GR to de-energize, and this opening 5 and 110 3^a clears down the entire connection without metering.

If, when S1 is speaking to the called subscriber, retaining circuit 5 be opened by a trunk circuit, CR1 and CR2 will de-energize, 115 causing the release of the connection without metering. Similarly if 3, 3^a or 3^b be opened for any like reason, BSR will de-energize releasing the connection without metering. Similarly if 10 be opened and RCR de-energized, an equivalent result is obtained.

It is to be noted that in such cases the calling subscriber will not take a new trunk leading from the pre-selecting stage, as LR cannot be re-energized unless he replaces his 125 receiver and starts a fresh call, as explained in Patent No. 1,225,291, dated May 8, 1917.

In the case of a call to the manual board, the call is set up in the same manner by S1 and IR but trunk T1 is connected to T3. 130

As before T3 may be at any group-switching stage but for the sake of clearness is explained as if it were connected at the first digit switching stage. 1 to 8 are completed 5 as before, and then BSR is maintained over 3^a (Figures 9 and 11). S2R is now energized before S1R over 16, and then TSR energizes over 16 and holds itself over 16^a. TSR removes IR, S1R and S2R from the 10 transmission circuit and a clear circuit is established from S1 over 17 to L3R and resistance R2, GR maintaining itself in circuit 4^a over contacts of BSR and TSR. L3R energizes and CL glows over 18, while 3^a is 15 switched through 3^a energizing RR.

It is obvious from the previous explanations that if S1 replace his receiver before the operator answers, BSR will de-energize and clear down the connection without caus- 20 ing metering.

If the operator answer, CO1R energizes over 19 cutting out L3R and lamp CL ceases to glow. RR maintains itself over 20 and 3^a is extended to 3^c. The operator can meter 25 by energizing MRR and shortcircuiting R1, thus causing MMR (Figure 9) to energize. MMR extends 5 to 5^c, shortcircuiting R and causing SM to energize. Clearing can only be accomplished by the operator withdraw- 30 ing the plug, as in the case of Figures 6 and 8.

Figure 14 represents an outgoing line from an operator's position to the automatic exchange, these lines terminating at the first 35 group switching stage. An operator desiring to establish a connection with an automatic subscriber first identifies a disengaged junction by observing the condition of the engaged lamps EL. She then inserts a plug 40 in jack J of a disengaged junction. 1 is completed and the usual supervisory signals in the operator's cord circuit glow in a well known manner. Resistance R is such that relay CO2R does not energize. I2R ener- 45 gizes over 2, but the resistance of this relay is such that the supervisory signal of the operator's cord circuit remains unchanged. 3 is completed and the engaging lamps per- taining to the junction taken glow. I2R 50 opens circuit 1 and relay CO2R energizes over 1^a. BSR energizes over circuit 4 in the manner explained for Figures 1 and 2.

It is to be noted that if this relay de-energizes through any cause, BR will energize, 55 effectively preventing the re-energizing of BSR. The operator sends in the impulses in a well known manner, and these are re-peated to the impulse selectors over 5 through DR, which does not energize. Even- 60 tually the junction T1 is connected accord- ing to Figure 2 to the called subscriber as previously explained. The called subscriber replying, DR energizes over 6 and maintains itself over 6^a, cutting out I2R thus establish- 65 ing a clear circuit from the operator's cord

to the called subscriber over 8. Should the subscriber be engaged at the time of calling, BSR would be de-energized thus energizing BR over 7, giving an interrupted tone to the operator setting up the connection. The 70 operator's supervisory signals operate in a well known manner, signaling the reply of the called subscriber. The operator controls the release of the connection, and this is accomplished by the withdrawal of the plug, 75 which opens 1^a, causing CO2R to fall off and opening 4.

Figure 13 represents a similar junction using a shortcircuited relay KR instead of the differential relay DR in Figure 14. The junction J2 joins up with Figure 7. When a connection is established, the operation of the circuit is as follows:

The operator inserting the plug in J2 completes 1 which energizes I3R, thus completing 2 and 2^a. Engaged lamps EL glow and BSR energizes as before. BSR completes 3, energizing G4R, which maintains itself through its own contact A, and the third wire of the operator's cord circuit BSR is transferred to 2^a and is therefore independent of the impulse relay I3R. The operator sends the impulses in the usual manner which are repeated to the selector over 4. When the called subscriber answers, KR is 85 energized over 5, maintaining itself over 5^a. A clear line circuit is now established to the called subscriber over 6. The release of the circuit is in the hands of the operator who by withdrawing the plug, will cause G4R to 90 de-energize, releasing KR and BSR and the connection throughout. The supervisory signals of the operator's cord circuit behave in the same manner as described for Figure 14. In the case of a call to a busy subscriber, 105 BSR will de-energize, thus giving interrupted busy tone to the operator by circuit 7.

What I claim is:

1. In automatic and semi-automatic telephone systems, the combination of subscribers' lines, battery feeding devices, discriminating means adapted in one condition to connect battery feeding devices to the lines of calling and called subscribers, and to place the control of the release of the connection with the calling subscriber, and in another condition to cut off said device from a calling line, and to place the control with an operator, means for altering the condition of such discriminating means, a third 110 conductor circuit and a relay in said circuit adapted on the circuit being extended to an operator to maintain the partially complete connection against release.

2. In automatic and semi-automatic telephone systems, the combination of subscribers' lines, battery feeding bridges, condensers, a pair of relays, one of which is attached to each line branch of a connection, and which are adapted to remove the feed. 125 130

- ing bridges and condensers from the connection, means at the called end of a connection for operating the pair of relays, and means for establishing a direct connection 5 between the calling and called subscribers.
3. In automatic and semi-automatic telephone systems, the combination of subscribers' lines, battery feeding devices, condensers, a manual switchboard, a trunk line 10 leading thereto, means for connecting a subscriber's line to the trunk line, and means for removing the feeding devices and condensers from an extended subscriber's line that has been connected over a trunk to the 15 switchboard before the operator answers the call.
4. In automatic and semi-automatic telephone systems, the combination of subscribers' lines, battery feeding devices, condensers, a manual switchboard, a trunk line 20 leading thereto, means for connecting a subscriber's line to a trunk line, means for removing the feeding devices and condensers from an extended subscriber's line that has 25 been connected over a trunk to the switchboard before the operator answers the call, and a slow acting relay adapted to be connected in the circuit, and to be operated when a calling line is extended to the trunk 30 line, and means for effecting the disconnection of the circuit during the time taken by such relay to de-energize.
5. In automatic and semi-automatic telephone systems, the combination of subscribers' lines, battery feeding devices, an impulse 35 repeating circuit, a differential relay connected to such circuit and adapted to be inoperative during the repetition of impulses but to be operated when a calling subscriber 40 is connected to another subscriber or to an operator.
6. In automatic and semi-automatic telephone systems, the combination of subscribers' lines, battery feeding devices, a 45 manual switchboard, a trunk line leading thereto and a differential relay attached to said trunk and adapted to be energized when a subscriber is connected to said trunk.
7. In automatic and semi-automatic telephone systems, the combination of subscribers' lines, battery feeding devices, discriminating means adapted in one condition 50 to connect battery feeding devices to a calling line, a manual switchboard, a trunk line 55 leading thereto and a differential relay attached to said trunk and adapted to be energized when the calling subscriber is connected to said trunk but de-energized and cut away from said trunk by said discriminating means.
8. In automatic and semi-automatic telephone systems, the combination of subscribers' lines, impulse senders, a relay adapted to feed current to a calling subscriber, a relay adapted to feed current to a called subscriber, means for connecting the calling and called subscribers, condensers in the connection and means for cutting away said relays and condensers during the 65 transmission of impulses.
9. In automatic and semi-automatic telephone systems, the combination of subscribers' lines, pre-selector switches, digit selector switches, a trunk connecting the switches, a device connected to the trunk 70 and adapted to feed current to a calling subscriber, condensers connected in said trunk, two relays, each of which is connected to one line branch of said trunk, adapted to feed current to the called end of the connection and means for energizing said relays according to the class of the connection 75 established.
10. In automatic and semi-automatic telephone systems, the combination of subscribers' lines, pre-selector switches, digit selector switches, a trunk connecting the switches, a device connected to the trunk and adapted to feed current to a calling subscriber, condensers connected in said 80 trunk, two relays, each of which is connected to one line branch of said trunk, adapted to feed current to the called end of the connection and means for completing a loop 85 through said relays when the trunk is extended to a called subscriber.
11. In automatic and semi-automatic telephone systems, the combination of subscribers' lines, a device adapted to feed current to a calling subscriber, a trunk, two 90 relays, each of which is connected to one line branch of said trunk, and means for energizing one of these relays from the called end of said trunk before the completion of the connection.
12. In automatic and semi-automatic telephone systems, the combination of subscribers' lines, a trunk, a device connected to the trunk and adapted to feed current 95 to a calling subscriber, condensers connected in said trunk, a manual switchboard, two relays, each of which is connected to one line branch of said trunk, means for connecting the trunk to the switchboard, means for energizing one of said relays before the 100 other when the trunk has been connected to the switchboard and means for removing said current feeding device, relays and condensers from the trunk.

HENRY JAMES HERINK.
